PUPPET OR THE LIKE

Walter B. Bartner and Howard C. Bartner,
Toms River, N. J.

Application March 10, 1950, Serial No. 8,476

Term of patent 3½ years

(Cl. D34—4)

To all whom it may concern:

Be it known that we, Walter B. Bartner and Howard C. Bartner, citizens of the United States of America, and both residents of the city of Toms River, in the county of Ocean and State of New Jersey, have invented a new, original, and ornamental Design for a Puppet or the like, of which the following is a specification, reference being had to the accompanying drawing, forming a part thereof.

Fig. 1 is a front view of a puppet or the like, showing our new design;

Fig. 2 is a rear view thereof; and

Fig. 3 is a side view thereof.

We claim:

The ornamental design for a puppet or the like, substantially as shown.

WALTER B. BARTNER.
HOWARD C. BARTNER.
